UNITED STATES PATENT OFFICE.

BERT R. PEOPLES, OF VALLEJO, CALIFORNIA.

GARMENT-PRESS.

1,111,969.

Specification of Letters Patent. Patented Sept. 29, 1914.

Application filed March 4, 1912. Serial No. 681,456.

To all whom it may concern:

Be it known that I, BERT R. PEOPLES, a citizen of the United States, residing at Vallejo, in the county of Solano and State of California, have invented certain new and useful Improvements in Garment-Presses, of which the following is a specification.

This invention relates to garment presses and more particularly to a means for pressing neckties of the four-in-hand and string 10 styles.

The object is to provide a press of small and handy size, in which that portion of the ties, which become wrinkled by continual tying and untying may be pressed when not in use. By its use a tie may be placed in the press over night and taken out in the morning, with all objectionable creases removed and in presentable condition 20 for wear.

To more clearly illustrate the invention, attention is called to the accompanying drawing, in which,

Figure 1 is a side elevation of my improved press, Fig. 2 a plan view, and Fig. 3 a transverse section on the line 3—3 of Fig. 2 on a larger scale and more nearly actual size.

The press comprises two separable boards 30 1 and 2, each having a flat face adapted to bear against the other, when in use. Arranged on opposite sides of the base board, and secured thereto, are longitudinal strips of sheet metal 3. One end of each strip is 35 turned upwardly and rearwardly to provide engaging members in the shape of extending arms or lugs 4, these lugs having their under surfaces inclined downwardly to form cam hooks. The opposite ends of the 40 strips 3 are arranged in a vertical position as illustrated at 5 forming supports for the pressure members or compressing springs 6. These springs are pivotally secured to the upper part of the supports 5 by means of 45 small upstanding lugs extending through openings in one end of the springs and loosely riveted, allowing the springs to be easily swung back and forth. The metal strips 3 are so arranged that the lugs 4 on 50 one side are placed directly across from the support 5, or the pivot points for the springs, on the opposite side of the base board.

The springs or clamping members 6 are 55 formed of flat resilient metal and are of the bowed variety, as illustrated at 7 in Fig. 3.

The free ends 8 of these springs are adapted to be swung around and engage the under surfaces of the lugs 4, which surfaces being inclined downwardly, force the springs to flatten out against the upper board thus exerting the required pressure upon the pressing members 1 and 2. It will be seen that by moving the free ends of the springs farther and farther along the inclined surfaces of 60 the lugs 4, the pressure may be increased accordingly.

Metal plates 9 are preferably secured on the top board at the points of frictional contact with the springs. While I have illustrated this in the drawings I do not care to limit myself to such a construction, as it is possible with my device, inasmuch as all the mechanism is carried on the lower board, to use either side of the upper board for the 65 pressing surface or use any flat object of the required shape and size. Between the boards 1 and 2 a cloth 10 is laid, and applied to the article to be pressed. This cloth is to be used dampened, to facilitate 70 the pressing operation.

The operation is readily understood. After laying the ties on the lower board and placing the dampened cloth in position, the upper board is laid on and the free ends of 75 the springs or clamping members are moved from the position, shown in dotted lines in Fig. 2, around under the lugs 3. The inclined surfaces of these lugs force the ends of the springs downwardly as they are 80 pushed forward, thus exerting the necessary pressure upon the two boards.

While I have shown and described a preferable form of device, I do not care to limit myself to the specific construction herein 85 illustrated, but what I claim as new is—

1. A garment press comprising a relatively stationary and a movable board, and a pair of clamping members secured to opposite sides of the stationary board, each 90 member comprising a strip provided at one end with an arm and at its other end with a pivot member, and a pressure member pivotally mounted on the pivot member of one strip and having its free end adapted 95 to engage with the arm of the other strip.

2. A garment press comprising a pair of boards, and a pair of similarly formed clamping members arranged on opposite sides of said boards, each of said members 100 comprising a strip secured to one of said boards and formed at one end with an up-

standing arm having a cam hook and at its other end with a pivot member, a spring pivotally mounted upon each pivot member and adapted to bear against the other of 5 said boards, the free end of the spring carried by each strip being engageable with the hook on the other strip.

3. A garment press comprising a pair of separable boards, a dampened cloth held between the said boards, longitudinal members secured to each side of one of said boards, pivots on one end of said longitudinal members and overhanging lugs on the other ends, said pivots and lugs being diametrically opposed, clamps attached to said pivots arranged to engage the other board and having their free ends secured under said lugs.

15 4. A garment press comprising a pair of

separable boards, a dampened cloth held between the said boards, longitudinal members 20 secured to each side of one of said boards, pivots on one end of said longitudinal members and overhanging lugs on the other ends, said pivots and lugs being diametrically opposed, inclined surfaces on the under sides 25 of said lugs, clamps attached to the pivots on said longitudinal members arranged to engage the other board and have their free ends secured under said lugs and contacting with said inclined surfaces.

30 In testimony whereof I hereunto affix my signature in presence of two witnesses.

BERT R. PEOPLES.
